UNITED STATES PATENT OFFICE.

WILLIAM H. FOWLER, OF SELMA, ALABAMA.

LINE-CHECK.

No. 918,988.

Specification of Letters Patent.

Patented April 20, 1909.

Application filed October 23, 1908. Serial No. 459,141.

To all whom it may concern:

Be it known that I, WILLIAM H. FOWLER, a citizen of the United States, and a resident of Selma, in the county of Dallas and State of Alabama, have made certain new and useful Improvements in Line-Checks, of which the following is a specification.

This invention is an improved line check for use in connection with injectors and boilers, and the invention consists in certain novel constructions and combinations of parts as will be hereinafter described and claimed.

In the drawing—Figure 1 is a longitudinal section of my improved line check, as in use. Fig. 2 is a cross section thereof on about line 2—2 of Fig. 1.

In the use of my invention my improved line check as shown in Fig. 1 is placed half way between the injector 1 and boiler check 2, and the purpose is to provide a simple construction which will insure the working of the injector when the boiler check is stuck or otherwise inoperative.

As shown, my line check comprises a casing A having a chamber B which is widened laterally to permit the play of the ball C and has its bottom wall provided in its upper side with a longitudinal channel B' in which the ball rolls from end to end of the chamber B and to which channel the ball will return by gravity. This chamber B affords at both sides of the ball passages for water, and the ball can readily roll to and from its seat B² at one end of the chamber B. It will be noticed that the base of the chamber B inclines downwardly toward the seat B² so that the ball will roll by gravity to the position shown in Fig. 1, and will thus be seated at all times except when the injector is at work. The ball is preferably made hollow and out of brass about one fourth of an inch thick, being thus more sensitive than a solid ball, and it is also preferred to make the cage or casing A of brass. At the other end of the chamber, I provide a strainer D in the form of a perforated cylinder projecting into the end of the chamber B opposite the valve seat B² so that water may pass around the ball C to the strainer D and thence to the boiler. The strainer D is held in place by its end flange D' fitting against a shoulder A' in the casing A and held thereto by the connection E screwing into place as shown in Fig. 1.

The end plate D² of the strainer is formed with a concave seat D³, and when the injector

is put on the ball will roll up against the strainer, as indicated in dotted lines, Fig. 1, and rest in the said seat and be thus held stationary until the injector is shut off when the ball will drop back to its seat as shown in Fig. 1.

When the boiler check sticks, the boiler pressure can only pass against the ball C forcing the same to its seat so that it will not affect the injector, as the injector will go to work any time, with boiler check stuck up, when the form of line check shown is employed.

As suggested, the casing is formed to provide ample water space within its chamber B, and the branch pipes may be conveniently connected with the opposite ends of the casing in coupling up the line check with the injector and boiler check as shown in Fig. 1 as before described.

I claim—

1. A line check substantially as herein described comprising a casing having a chamber provided at one end with a valve seat and the said chamber being extended laterally and vertically, a ball operating in said chamber to and from the ball seat and of a diameter less than the lateral and vertical diameter of the interior of the chamber whereby to afford water space, and a strainer in the other end of the casing and having a tubular portion projecting into the chamber substantially as set forth.

2. A line check comprising a casing having a ball chamber and provided at one end with a valve seat and at its other end with a strainer, and a ball in the chamber between the valve seat and strainer and movable therein between the valve seat, and the strainer and against one or the other of said parts in the different positions of the ball substantially as set forth.

3. A line check comprising a casing having a chamber provided at one end thereof with a valve seat, a strainer at the other end of the casing, and a ball valve in the chamber between the strainer and valve seat and movable toward and from said seat, substantially as set forth.

4. A line check substantially as herein described comprising a cage or casing having a valve seat at one end, and a strainer at its other end, the said strainer being provided with a concave seat and the bottom of the cage or casing inclining downwardly toward the valve seat, and a valve movable in the

cage or casing between the valve seat and the strainer and seating in one position in the concave seat of the strainer, all substantially as and for the purposes set forth.

5. A line check comprising a casing having a chamber and a valve seat at one end thereof, a strainer in the other end of the chamber and having a concave seat facing toward the valve seat and a ball valve in the chamber and movable between and against the valve seat and the strainer seat, substantially as set forth.

10. A line check substantially as described, comprising a casing having a chamber and

provided at one end thereof with a valve seat 15 and having in the bottom of said chamber a longitudinal channel extending in the direction of the valve seat, the chamber being extended laterally on opposite sides of the said longitudinal channel, a strainer at the other 20 end of the chamber from said valve seat and a ball in the chamber and movable in the longitudinal channel thereof toward and from the valve seat, substantially as set forth.

WILLIAM H. FOWLER.
